UNITED STATES PATENT OFFICE.

CARRIE EDGARDA KIDDER, OF SOMERVILLE, MASSACHUSETTS.

BAG.

Application filed December 7, 1920. Serial No. 428,879.

To all whom it may concern:

Be it known that I, CARRIE EDGARDA KIDDER, a citizen of the United States, and a resident of Somerville, in the county of Middlesex, State of Massachusetts, have invented an Improvement in Bags, of which the following description, in connection with the accompanying drawings, is a specification, like characters on the drawings representing like parts.

This invention pertains to improvements in bags, and more particularly, though not exclusively, to bags of the type used largely by women and called shopping bags or opera bags. The invention is, however, applicable to other types of bags, such as school bags, knitting bags and bags for other purposes.

It is among the objects of the invention to provide a bag of simple construction, not likely to get out of order, which can be readily opened and closed by the user when desired, and which cannot be opened accidentally when in normal use or without the knowledge of the user.

In the drawings, which show an illustrative form of a preferred form of my invention:

Figure 1 is a front elevation of a bag constituting a preferred embodiment of one form of my invention;

Fig. 2 is a plan view of the bag, shown in Fig. 1, when open;

Fig. 3 is a front elevation of the bag when open, a hand being shown in dotted lines to illustrate the preferred way of entering the bag illustrated, as for removal of articles therefrom; and

Fig. 4 is a section on the line 4—4 of Fig. 2.

Referring to the drawings and to the preferred form of my invention selected for illustrative purposes, I have shown a bag providing a depending container 5, preferably of flexible material such as cloth or the like, and provided with an opening 6 at its top through which articles may be introduced into the bag or removed therefrom. The opening 6 is preferably, as illustrated, provided with a shaped gathering element, preferably rigid and preferably taking the general form of a ring 7, which may to advantage be, as illustrated, oval in shape. The ring 7, as illustrated, is assembled with the flexible portions of the bag in such a way that it may gather the greater portion of

the material surrounding the opening in the bag, a sufficient portion of the material adjacent the opening of the bag preferably being free of the gathering element so as to permit the material to pass over a diameter of the ring, or gathering element, that the bag may be opened by turning the ring in a plane generally transverse to the general plane of the bag and preferably in a direction toward that side of the opening in the bag which is free of the gathering element. The ring or gathering element is preferably of such proportions as to admit the hand of the user to pass through the ring into the interior of the ring as illustrated in Fig. 3. The gathering means is preferably assembled with those portions of the bag adjacent the opening therein sufficiently freely so that the bag will close when the gathering element is tipped into the general plane of the axis of the bag, or in a generally vertical direction, this closure being effected by the action of gravity on the bag or on the bag and the contents thereof. Where the gathering element is oval shaped, the closure of the bag is somewhat more complete than where the gathering element is round. It is obvious that a gathering element of any suitable shape might be substituted, and that a gathering element having at least one end narrowed will provide the increased gathering capability inherent to the oval illustrated and described.

The ring, being of sufficient amplitude readily to admit the hand of the user, is also preferably of sufficient amplitude to permit the arm of the user to pass therethrough to carry the bag. When the bag is thus carried, it cannot be accidentally opened, and it cannot be opened without the knowledge of the person carrying the bag.

The details of carrying out my invention may be greatly varied, but I prefer that the depending portion of the bag shall be made entirely of flexible material, as illustrated, and that this flexible material be doubled to provide an outside portion and a lining portion. I prefer that the outside portion and the lining portion be connected as by being sewn together at the bottom 8, as best shown in Fig. 4, and I prefer that the gathering element shall fit loosely between the outside fabric and lining fabric so that there will be as little resistance as possible to opening and closing of the bag, those portions of the fabric which in the preferred form of my in-

vention pass over the ring being freely slideable on the ring.

In the preferred form of my invention selected for illustrative purposes, I have provided as a part of the periphery of the opening of the bag adjacent that portion thereof where the ring is exposed when the bag is open, a slit 9 having the corners of the adjacent fabric turned down as at 10, 10 to provide an ornamental and finished effect. The slit serves a useful function, viz, to permit the gathered portions of the bag to pass over a diameter of the rigid gathering means, herein typified by the ring 7. This slit may be enlarged somewhat beyond the amount necessary to perform the above mentioned function so that small articles may be dropped into the bag without passage thereof through the ring pursuant to opening of the bag, as illustrated in Figs. 2 and 3. The space afforded by the slit is, however, preferably sufficiently small so that a hand could not be introduced into the bag through the slit without the knowledge of the one carrying the bag.

When normally carried in the hand or on the arm of the user, the bag parts occupy the general position illustrated in Fig. 1. When the bag is to be opened for the introduction of an article of a considerable size or for the removal of articles therefrom, the upper portion of the ring 7, as viewed in Fig. 1, may be grasped and the ring tipped into horizontal plane, the upper portion of the ring as viewed in Fig. 1 being inclined toward that side of the bag having the slit therein. The gathered portion of the bag may then be readily drawn about the ring and the hand of the user inserted as viewed in Fig. 3. When it is again desired to close

the bag, the exposed portion of the ring 7, illustrated in Fig. 3, may be grasped and the ring permitted to tip into vertical position, thus causing the material to slide over the ring and to be gathered at the lower end 45 thereof. Where the ring is oval or provides a narrowed end and where this narrowed end is downward the gathering action is accentuated as before described.

While I have shown and described a preferred embodiment of my invention, it will be understood that major changes involving omission, alteration, substitution and rearrangement of parts may be made without departing from the scope of my invention, 55 which is best defined in the following claims.

Claims:

1. The combination of a bag of flexible material having an opening at the top, with 60 a rigid ringlike gathering element at the opening of the bag, the union between the bag and the gathering element being a loose one free of any restricting stitching or seams and permitting considerable play or freedom of movement of the bag relative to the gathering element, said movement being permitted not only about the perimeter of the gathering element but also longitudinally of the bag, the gathering element having a narrowed portion, whereby when the gathering element is held in a substantially vertical position with the narrowed portion lowermost the bag is freely gathered and closed under the influence of gravity. 75

2. The combination of claim 1, wherein the rigid gathering element is oval.

In testimony whereof, I have signed my name to this specification.

CARRIE EDGARDA KIDDER.
